[57] ABSTRACT

3-(N- β , γ -dihydroxypropyl-acetyl-amino)-5-acetylaminomethyl-2,4,6-triiodobenzoic acid and its non-toxic, water-soluble salts with alkali metals and amines are better tolerated by the central nervous system for intracerebral and intracisternal application than X-ray contrast agents available heretofore for cerebral angiography. They are preferentially excreted from the blood by the kidney in a manner to make them useful for urography.

4 Claims, No Drawings

CONTRAST AGENT FOR ANGIOGRAPHY AND UROGRAPHY

This invention relates to X-ray contrast agents, and particularly to contrast agents suitable for angiography and urography which are derivatives of 2,4,6-triiodobenzoic acid.

It has been found that 3-(N- β , γ -dihydroxypropyl-acetyl)-amino-5-acetylaminomethyl-2,4,6-triiodobenzoic acid of the formula

and its non-toxic, water-soluble salts with alkali metals and amines are better tolerated by the central nervous system than contrast agents available heretofore, being particularly superior to the known compounds in their low intracerebral and intracisternal toxicities. They are generally suitable for vasography, and particularly for cerebral angiography.

The following Table shows toxicity values for the compound of the invention (Compounds A and A'), for the structurally closely related 3-(N- β -hydroxyethyl-acetylamo)-5-acetylaminomethyl-2,4,6-triiodobenzoic acid (Compound B, German published patent application No. 1,928,838, Example 5), and for Iodamide (Compound C, 3-acetylamo-5-acetylaminomethyl-2,4,6-triiodobenzoic acid, U.S. Pat. No. 3,360,436) which is representative of the best contrast agents available heretofore for cerebral angiography.

Compounds A, B, and C were employed in the form of their N-methylglucamine salts, and Compound A' as the corresponding sodium salt of the invention. All listed toxicity values are expressed as LD₅₀ in mg iodine per kg of test animal, the intravenous and intracerebral toxicity being determined in mice, and the intracisternal toxicity in rabbits. Identical standardized test conditions were maintained for each tested compound in each group of tests, and the tests of each group were performed at the same time so that the test results for the several compounds are directly comparable.

In testing toxicity after intravenous injection, the aqueous solutions employed contained 300 mg iodine per milliliter and were injected at a rate of 20 g iodine per minute per kg of test animal weight. In all tests for intracerebral toxicity, the amount of aqueous test solution was 2 ml per kg of body weight, and the concentration was varied to modify the dosage. All solutions used for testing intracisternal toxicity contained 280 mg iodine per milliliter. Hyphens in the Table indicate that the test was not performed.

Table

Compound	Toxicity, LD ₅₀ , mg I per kg					
	Intravenous		Intracerebral		Intracisternal	
	24 hrs.	12 days	48 hrs.	12 days	48 hrs.	12 days
5						
A	6600	6600	285	—	39	29.4
A'	7400	—	285	—	38	—
B	5800	5700	120	—	21	—
10						
C	6600	6600	97	—	20	—

As is evident from the values for intravenous toxicity, the compounds of the invention are at least as well tolerated generally as Iodamide (Compound C) which has been in extensive clinical use. In their most important property, the tolerance by the central nervous system, the compounds of the invention are superior by a wide margin to Compounds B and C, both in intracerebral application to mice and in intracisternal application to rabbits.

The free acid of Compound A is primarily useful as an intermediate in the preparation of the water-soluble salts with pharmaceutically acceptable alkali metals and amines. Sodium is the preferred alkali metal. The lithium salt may also be employed. The other alkali metals contribute physiological properties of their own which are not normally desirable. Small amounts of the calcium or magnesium salts may be employed jointly with the alkali metal salts.

The amines employed are those commonly used in galenic pharmacy as physiologically inert, cationic moieties in salts of physiologically active acids. They include, but are not limited to N-methylglucamine, N-methylxylamine (1-methylamino-1-dsoxy-[D]-xylite), 1-methylamino-2,3-propanediol, monoethanolamine, diethanolamine, tris-(hydroxymethyl)-aminomethane, and mixtures of such alkanolamines.

The free acid of Compound A is prepared by alkylating 3-acetyl-amino-5-acetylaminomethyl-2,4,6-triiodobenzoic acid in strongly alkaline solution with an ester of the formulas X — CH₂ — CH(OH) — CH₂OH or

wherein X is the anionic radical of a strong acid, such as a hydrogen halide (HCl, HB_r, HI), an alkylsulfonic acid, or an arylsulfonic acid. An epoxide may replace the esters. The most conveniently available alkylating agents include 3-chloro-1,2-propanediol, 3-bromo-1,2-propanediol, 3-iodo-1,2-propanediol, 3-benzenesulfonyloxy-1,2-propanediol, 3-toluenesulfonyloxy-1,2-propanediol, 3-methanesulfonyloxy-1,2-propanediol, 2,3-epoxy-1-propanol, epichlorohydrin, 1-benzenesulfonyloxy-2,3-epoxypropane, and 1-methanesulfonyloxy-2,3-epoxypropane.

The alkylation is preferably performed in alcoholic solution in the presence of an alkali metal alcoholate as an acid acceptor. The aqueous solutions of the salts are prepared by dissolving the free acid in aqueous solutions of equivalent amounts of a base, and the salts may be recovered from the solutions in solid form, if so desired, by evaporating the solvent in a vacuum.

The salts are dissolved in enough water to provide injectable solutions containing preferably between about 140 and 600 mg iodine per milliliter, and the solutions are injected in a conventional manner observing the

precautions well established by the use of Iodamide when it is desired to make blood vessels, particularly those of the brain, visible in X-ray images.

The solutions are also employed to advantage in urography. It has been found that the two hydroxyl groups in the side chain in position 3 do not materially interfere with excretion of the compound by the kidney so that at least 60% to 70% of an intravenous dosage of 100 mg per kg body weight is discharged by the kidney of standard laboratory test animals within three hours. A sufficient amount of the radiopaque material is thus available in the urinary system for producing X-ray pictures of good contrast. Otherwise closely related compounds having more than two hydroxyl groups in side chains of the basic triiodobenzoic acid molecule do not produce useful X-ray images of the urinary tract.

The following Examples are further illustrative of the invention.

EXAMPLE 1

50.2 g 3-Acetylamino-5-acetylaminomethyl-2,4,6-triiodobenzoic acid (0.08 mole) was dissolved in 400 ml methanol, and the solution was mixed sequentially with 128 ml 2.5-molar sodium methylate solution (0.32 mole) in methanol and 13.4 ml 3-chloro-1,2-propanediol (0.16 mole). The mixture was stirred at ambient temperature (about 20°C) for 24 hours. An additional 32 ml 2.5-molar sodium methylate solution (0.08 mole) and 6.7 ml 3-chloro-1,2-propanediol were admixed, and stirring was continued for 24 hours.

The reaction solution was diluted with 400 ml water, neutralized with acetic acid, evaporated to one half of its original volume, and acidified with hydrochloric acid. It was then stirred overnight at ambient temperature, and the precipitate formed was recovered by suction filtration. The almost pure 3-(N-β,γ-dihydroxypropyl-acetylamino)-5-acetylaminomethyl-2,4,6-triiodobenzoic acid so obtained weighed 49.5 g (88% yield). When recrystallized from aqueous, approximately 40% ethanol, it melted at 195°–197°C and had an equivalent weight of 709 (calculated: 702). It was further identified by elementary analysis:

Calculated for C₁₈H₁₇I₃N₂O₆
Found

C 25.66%
25.65

I 54.23%
53.63

A thin layer chromatogram on silica gel with butanol/water/glacial acetic acid 3/2/1 gave a R_f value of 0.57.

The free acid is soluble in 40 times its own weight of boiling water, 7 weights of cold methanol, 3 weights of boiling methanol, 50 weights of cold ethanol, and 5 weights of boiling ethanol, but is insoluble in chloroform. The salts with the alkali metals and amines mentioned above are readily soluble in water, the sodium and N-methylglucamine salts dissolving at 20°C in about their own weights of water.

EXAMPLE 2

Four batches of 25.1 g 3-acetylamino-5-acetylaminomethyl-2,4,6-triiodobenzoic acid were dissolved in respective 380 ml batches of a 0.5-molar solution of sodium methylate in methanol, and the solutions so obtained were mixed with 18.6 g 3-bromo-1,2-propanediol, 24 g 3-iodo-1,2-propanediol, 20 g 3-methanesulfonyloxy-1,2-propanediol, and 28 g 3-

benzenesulfonyloxy-1,2-propanediol respectively and stirred with a turbine type agitator for 60 hours.

3-(N-β,γ-dihydroxypropyl-acetylamino)-5-acetylaminomethyl-2,4,6-triiodobenzoic acid was recovered from each reaction mixture in the manner described in Example 1. The products had melting points between 194° and 198°C, and the yields varied between 75% and 90%.

EXAMPLE 3

10 12.55 g 3-Acetylamino-5-acetylaminomethyl-2,4,6-triiodobenzoic acid (0.02 mole) was dissolved in 80 ml of a 0.5 molar solution of sodium methylate in methanol, and 4 g 2,3-epoxy-1-propanol was added. The mixture was stirred for 1 hour at ambient temperature and stored thereafter for 60 hours. It was then worked up as in Example 1 to recover 10.5 g 3-(N-β,γ-dihydroxypropyl-acetylamino)-5-acetylaminomethyl-2,4,6-triiodobenzoic acid melting at 196° to 198°C (74.7% yield).

EXAMPLE 4

15 553 g 3-(N-β,γ-dihydroxypropyl-acetylamino)-5-acetylaminomethyl-2,4,6-triiodobenzoic acid, 136.7 g N-methylglucamine, and 3.6 g sodium hydroxide were added sequentially with stirring to a solution of 0.01 g disodium edetate in a small amount of bi-distilled water, and adding enough additional water to produce 800 ml solution. The solution was adjusted to pH 7.1±0.2, subjected to ultrafiltration, distributed in glass vials in amounts of 10 and 20 ml, and sterilized.

20 The injectable solutions so obtained contained 375 mg iodine per milliliter.

EXAMPLE 5

25 553 g 3-(N-β,γ-dihydroxypropyl-acetylamino)-5-acetylaminomethyl-2,4,6-triiodobenzoic acid, 31.5 g sodium hydroxide, 0.02 g disodium edetate, and enough bi-distilled water to make 1000 ml were combined as in Example 4. The solution was adjusted to pH 7.1±0.2, distributed in multiple puncture vials of 100 and 200 ml capacity and sterilized. It contained 300 mg iodine per milliliter.

30 What is claimed is:

1. A compound which is the 3-(N-β,γ-dihydroxypropyl-acetylamino)-5-acetylaminomethyl-2,4,6-triiodobenzoic acid of the formula

50 or a water-soluble salt of said acid with a pharmaceutically acceptable alkali metal or amine.

55 2. A compound as set forth in claim 1 which is said acid.

60 3. A compound as set forth in claim 1 which is a salt of said acid with sodium, lithium, or an alkanolamine.

65 4. A compound as set forth in claim 1 which is a salt of said acid with an alkanolamine selected from the group consisting of N-methylglucamine, N-methylxylamine, 1-methylamino-2,3-propanediol, monoethanolamine, diethanolamine, and tris-(hydroxymethyl)-aminomethane.
